Dec. 950

Nicholas Muller, of New York, N.Y.
Letters Patent No 950. Dated Oct 13th 1857

The schedule referred to in these Letters Patent making part of the same.

To all whom it may concern:

Be it known that Nicholas Muller of the City of New York, county and State of New York have invented or produced a new and original design for the fronts of Clock-cases, and I do hereby declare that the following is a full and exact description of the same, reference being had to the accompanying drawings, and to the letters of reference marked thereon.

Fig: 1. represents the front view:

Fig: 2. a side view from the right:

Fig: 3. a section in the line y.z. of Fig: 1.

The middle field a. of the pedestal as represented in fig: 1. contains the pendulum hole with arabesques on each side: the side fields of the pedestal are rounded and contain ornaments as shown in fig: 1 and 2.

The middle field a. bears a kind of capital b. with 5 protruding balls: above the column is the frame for the dial hole. On each side of the capital b. is the figure of a dolphin with the head resting on the side field of the pedestal, the tails swung up to the frame of the dial-plate.

The upper part of the ornaments, as shown in fig: 1. consists of a female figure, in resting position, a wreath of leaves on the head, her left arm laid around the shoulders of a child which holds a lyre over the dial.

What I claim as my invention and desire to secure by Letters Patent is.

The design of the two dolphins and the design of the figure of the female with the child holding
